UNITED STATES PATENT OFFICE.

HENRY H. HOLDEN, OF PORT HURON, MICHIGAN.

STOVE.

SPECIFICATION forming part of Letters Patent No. 693,862, dated February 25, 1902.

Application filed March 12, 1901. Serial No. 50,831. (No model.)

To all whom it may concern:

Be it known that I, HENRY H. HOLDEN, a citizen of the United States of America, residing at Port Huron, in the county of St. Clair 5 and State of Michigan, have invented certain new and useful Improvements in Stoves, of which the following is a specification, reference being had therein to the accompanying drawings.

10 This invention relates to stoves and furnaces, and particularly to that class known as "magazine-stoves."

The object of the invention is to produce a stove in which the magazine is divided into 15 compartments with means for controlling the draft therethrough.

A further object of the invention is to provide novel means for conveying the gas and products of combustion which may rise in the 20 magazine to the fire-bed, and, furthermore, for retarding the combustion on one side of the magazine.

The invention consists in the details of construction and in the arrangement and combination of parts to be hereinafter more fully 25 set forth and claimed.

In describing the invention in detail reference will be had to the accompanying drawings, forming part of this specification, where- 30 in like characters denote corresponding parts in the views, and in which—

Figure 1 is a sectional view of a stove, showing the magazine in elevation with parts broken away. Fig. 2 is a top plan view, partly 35 in section. Fig. 3 is a perspective view of a fragment of the magazine.

In the drawings, 1 denotes the base, 2 the casing, 3 the top, and 4 the smoke-uptake, of a stove, all of any ordinary construction, 40 which may not therefore be described in detail. The products of combustion of the coal in the fire-box will find their way to the smoke-uptake 4 in the usual way, while the gas generated in the magazine will pass off through the 45 casing 13, coursing downward to the fire-box, where it is consumed or carried to the smoke-uptake. The magazine comprises a cylindrical body 5, provided with a channel 6. The inner walls of the meeting edges of the body 50 are also provided with channels 7. A central partition 5^a has its edges embedded in the

channels 6 and 7 and is clamped therein by the screws or rivets 8 in the apertures of the lugs 9. A shoulder 10 is formed in the inner wall of the magazine near the top, and a semi-circular shutter 11 is slidable thereon. A pivotal pin 12 is run through the edge of the shutter and has its end embedded in the upper end of the partition.

From an inspection of Fig. 3 it will be seen 60 that the compartment in either side of the partition may be closed by swinging the edge of the shutter parallel with the partition.

A casing 13 is secured on the outer wall of the magazine, forming a hot-air passage 65 closed at the top and open at the bottom, and a hole 14 is cut in the body of the magazine, by which the magazine above the shutter communicates with the passage. The products of combustion and the gas generated by the heat 70 which often collects above the coal will be carried off through the hole 14 in the direction of the arrow, Fig. 1, down the air-passage to the fire-bed.

Lugs 15 are formed on the body, and the 75 magazine is suspended in the stove thereby.

In using the invention for burning soft coal the compartments of the magazine may be filled, and when the shutter is adjusted to close the top of the compartment the gases 80 and products are confined and combustion in the closed compartment is retarded. The coal is more readily consumed, owing to the draft through the magazine and the passage in the casing, and the passage in the casing 85 also conveys the products of combustion collecting at the top of the magazine to the fire-pot, where they are consumed.

In case it is decided to have the coal in both compartments consumed with the same rapidity the shutter may be set in the position shown in Fig. 3.

The construction, operation, and advantages will, it is thought, be understood from the foregoing description, and it is noted that 95 various changes in the proportions and details of construction may be resorted to for successfully carrying the invention into practice.

Having thus fully described the invention, 100 what I claim as new, and desire to secure by Letters Patent, is—

In a stove, a magazine, a partition therein, a shoulder formed on the inner wall of the magazine, a shutter pivoted on the partition and slideable on the shoulder, a casing forming a passage in communication with the magazine and means for suspending the magazine in the stove.

In testimony whereof I affix my signature in the presence of two witnesses.

HENRY H. HOLDEN.
